UNITED STATES PATENT OFFICE.

FRANK J. STOLLE, OF FORT THOMAS, KENTUCKY.

SHOE-SHINING KIT.

1,144,568.

Specification of Letters Patent. Patented June 29, 1915.

Application filed November 1, 1913. Serial No. 798,696.

To all whom it may concern:

Be it known that I, FRANK J. STOLLE, a citizen of the United States, residing at Fort Thomas, in the county of Campbell and 5 State of Kentucky, have invented new and useful Improvements in Shoe-Shining Kits, of which the following is a specification.

My invention relates to improvements in portable shoe shining kits, and is particularly adapted for home and office use.

My device is made of metal throughout, is very light and inexpensive to manufacture, and yet when set up for use is rigid and firm. Suitable receptacles are provided for 15 all the necessary brushes and blacking. When set up for use, the device has a broad, firm base, well braced, and when collapsed for carrying, the whole kit is very compact and is not liable to get out of order. No 20 parts are detachable. Therefore there is nothing to be lost and the time consumed in setting it up for use or letting it down for carrying, is but a few seconds, requires no skill and but one operation.

25 In the particular embodiment of my invention selected for illustration:—Figure 1 is a side elevation of the shoe shining kit set up ready for use, with the brushes and blacking box in position; Fig. 2 is an elevation of the device without brushes and blacking box, collapsed ready for carrying, with parts shown sectionalized; Fig. 3 is a detail of the bottom piece; Fig. 4, a detail, is a top plan view of the sliding ring that 30 holds the feet, with spring catch removed, legs partly broken away, and brush cage with brushes in position; and Fig. 5 is a detail of the foot rest.

Referring now to the drawings, A is the 40 bottom into which the lower ends of the upright rods B, B¹, B², fit snugly at a, a¹, a², respectively. The brush case C made of sheet metal, is secured to the bottom A by having projections c on the lower edge of 45 the case, passed through openings a³ and bent over. The footrest D has holes d, d¹, d², into which the top ends of the upright rods B, B¹, B², respectively, fit snugly. The 50 foot rest D has one or more conveniently placed fins, d³, to be used in opening the blacking box. The bottom, top and upright rods together form a fixed and rigid frame, and the bottom A forms the bottom 55 of the brush case.

Near the top of the upright rod B is a lug b. A swinging bracket E adapted to hold

a blacking box is loosely pierced by the rod B and has notches e, adapted to engage the lug b to hold the bracket E when in various positions. A spring S keeps the bracket 60 pressed down against the lug b. The bracket is meant to be swung out when the kit is set up for use. A ring R fits over the upright rods, and has suitably elongated and hollowed guides r, r¹, r², adapted to 65 seat upon the rods B, B¹, B², respectively, and slide thereon smoothly and with slight friction. On the ring at the back of each guide is a projection bored to receive the pivot l, that fastens the legs L to the ring 70 R. Each leg has a link l¹, the outer end of which is bent and fits loosely in a hole l² in the leg L, and the inner end of which is bent and fits in the contiguous hole a⁴ of 75 the bottom A. A projection l³ on the end of each leg at the top is adapted to seat snugly against the ring R and brace the leg when extended for use.

At the back of the ring is fixed a leaf spring N with a catch n at its lower end, 80 adapted to hook over the back of the bottom at a⁵ when the legs are extended and the kit is set up for use. When the ring R is so secured to the bottom A, the legs together form a rigid tripod stand and the 85 whole kit is firm and steady. The spring N has a catch n¹ at its upper end adapted to hook over the back of the slat d⁴ of the foot rest D when the kit is folded up ready to 90 be put away.

When the kit is set up ready for use as shown in Fig. 1, it is folded to be put away by pressing back the hook n so as to release it from contact with the bottom A, and the ring then slid upward until the hook n¹ 95 engages the bar d⁴ of the footrest. The kit is set up by reversing the operation.

I claim as my invention and desire to secure by Letters Patent of the United States:—

1. A shoe shining kit, having in combination a frame having a single vertical guide at the front, and a plurality of vertical guides at the rear, a vertically-disposed case confined between the lower portions of 105 the guides adapted to receive a brush, a foot rest supported on the upper ends of said guides, a ring circumscribing the brush containing case and slidably mounted on said guides, legs pivoted to said ring, and a link 110 connecting each leg with said guides.

2. An improved shoe shining kit, having

in combination a frame composed of a front vertical guide and two rear vertical guides, a case confined between the lower ends of said guides having a top opening adapted to receive a brush, a foot rest fixedly supported on the upper ends of said front and rear guides, a ring circumscribing said case and slidably mounted on said guides, a leg whose inner end at the top is adapted to 10 press against the ring in extended position, pivoted to said ring back of each vertical guide, a lever for each leg whose inner end is pivoted to a contiguous portion of the

bottom of one of said guides and whose outer end is pivoted to the leg toward the middle thereof, and a catch adapted to secure the ring to the bottom of the frame in set up position, and to the top of the frame in folded position.

In testimony whereof I have hereunto set 20 my hand in presence of two subscribing witnesses.

FRANK J. STOLLE.
